CEILING LIGHTING FIXTURE

Josef Müller, Neheim-Hüsten, Germany, assignor to
Lenze KG Lichttechnische Spezialfabrik, Neheim-
Hüsten, Germany

Filed Nov. 29, 1960, Ser. No. 63,023

Claims priority, application Germany June 7, 1960

Term of patent 7 years

(Cl. D48—23)

FIG. 1

FIG. 4

FIG. 2

FIG. 3

FIG. 1 is a perspective view of a ceiling lighting fixture showing my new design;

FIG. 2 is an elevation thereof as seen from the opposite side of FIG. 1;

FIG. 3 is an elevation thereof as seen from the right of FIG. 1; and

FIG. 4 is a bottom plan view thereof.

I claim:

The ornamental design for a ceiling lighting fixture, as shown.
